UNITED STATES PATENT OFFICE

DONALD H. MONTGOMERY, OF BERLIN, CONNECTICUT

DESIGN FOR AN AUTOMOBILE

Application filed February 12, 1931. Serial No. 38,634. Term of patent 14 years.

To all whom it may concern:

Be it known that I, DONALD H. MONTGOMERY, a citizen of the United States, and a resident of Berlin, in the county of Hartford, State of Connecticut, have invented a new, original, and ornamental Design for Automobile, of which the following is a specification, reference being had to the accompanying drawing, forming part hereof.

In the accompanying drawing:

The figure is a perspective view of an automobile showing my new design. The opposite side of the design is substantially the same as that shown.

I claim:

The ornamental design for an automobile as shown and described.

DONALD H. MONTGOMERY.
